BARBER'S MARGINAL TRIMMING DEVICE

Keith G. Johnson, Seattle, Wash.

Application May 25, 1953, Serial No. 357,186

5 Claims. (Cl. 30—210)

My present invention relates to the general plan of hair clippers and more particularly to an electric razor in which the cutting blades are curved so that when the cutting blade is held at right angles to the scalp the hair around the ear will be trimmed to a desired form giving the usual clearance around the ear. This invention may more properly be considered as an outlining arrangement and it is intended that it merely cut the ends of the hair so as to produce the desired clearance around the ear. To function for this purpose, it is necessary that the blade be curved and be double-edged so that the cutting can be done on either the right or left side of the head.

In many fields it is necessary for barbers to serve a large clientele and to be able to cut the hair of customers with a minimum of time being expended. Then, too, in so many instances, this type of barbering often is done by persons of somewhat limited training and experience, and these people need every possible aid in order that they achieve a truly presentable finished piece of work.

In the cutting of hair, the one point that goes a long way in determining the appearance of the haircut is how the hair is cut away from the ears. Barbers long skilled and who take sufficient time can do this trimming by eye and do it very accurately because of long experience. My present device however is intended to provide a mechanical means that will be electrically operated and which in one setting will accurately trim the hair to a very definite line. This trimming will be the final line and will be precise and accurate, with both sides of the head being just the same. When the exact contour of the clearance line around the ears is thus established, it then is a relatively simple matter to cut all the hair below this marginal line.

The principal object of this present invention therefore is to provide an electric razor or clipper having a curved blade adapted to be used with the transverse axis of the blade at right angles to the scalp and to have the blade curved so as to complete in a single setting the marginal clearance line around a customer's ear.

A further object of this invention is to provide an electric razor type of clipping action wherein the blades are formed in a curve and means provided so that one of the blades can reciprocate in the cutting action.

A further object of this invention is to have a curved cutting head for an electric razor in which a movable blade is sufficiently flexible so that it may change its curvature slightly as it performs the cutting operation.

A further object of this invention is to provide a handle portion for the razor which will house the driving motor and which will be hingedly joined to the cutter head so that it may be swung out of a position normal to the razor and thus provide adequate clearance when used on either side of a customer's head.

Further objects, advantages and capabilities will be apparent from the description and disclosure in the drawings, or may be comprehended or are inherent in the device.

2

In the drawings:

Figure 1 is a plan view illustrating this present invention;

Figure 2 is a side elevation showing the cutting bars and the supporting mechanism, certain parts being broken away to better illustrate the structure;

Figure 3 is an enlarged cross-sectional view, taken along the line 3—3 of Figure 1;

Figure 4 is a cross-sectional view taken along the line 10 4—4 of Figure 1;

Figure 5 is an enlarged sectional view through the driving motor and its enclosing handle and showing parts of the cutting bar supporting and driving mechanism;

Figure 6 is a fragmentary perspective view illustrating the power delivery end of the motor housing handle; and

Figure 7 is a perspective view of the position assumed by my invention when in use.

Referring more particularly to the disclosure in the drawings, the numeral 10 designates the main supporting 20 or base member of my cutter head. This unit is curved after the showing of Figure 1 and is provided with outstanding lugs as 12 and 14. Within lugs 12 and 14, as illustrated in Figure 5, are formed the conical recesses 16 adapted to receive similarly coned male detents 18. This arrangement provides a pivot so that the motor housing and handle 20 may swing on these pivots after the showing of Figure 4. It has been found that the maximum swing required does not exceed 45 degrees from each side of normal. A spring-loaded ball or detent 22 is secured 30 within lug 14 and is adapted to seat within any one of a plurality of depressions within housing 20 so that the handle can be angularly adjusted with respect to the cutter head and held in that position.

Secured to base member 10 is the stationary cutter bar 35 24 which is secured to the same by a plurality of machine screws indicated at 23. These screws secure the bowed guard member 32 in resilient engagement with the movable cutter bar 26 and in fixed engagement with the bushing-like abutment 25, through which screws 23 pass.

40 Disposed in contact with cutter bar 24 is the movable cutter bar 26. A study of Figures 3 and 4 will indicate that contact is made between the cutter bars only near the toothed portions. The teeth as illustrated are somewhat exaggerated in size but they should approach rather closely the tooth size of the standard electric razor as 45 distinct from a hair clipper. Bar 24 is provided with teeth as 28 and cutter bar 26 is provided with teeth at 30. Normally it is desirable that teeth 30 do not extend entirely out to the end of teeth 28. This distance should

50 only be a few thousandths of an inch as the intent is to have the weight of the cutter head rest against the skin on teeth 28 so that the movement of the teeth 30 in their position, at right angles substantially to the skin, will not touch the skin or cause abrasion. Outside of cutter bar 30 is the outer bowed guard member 32. This guard 55 as will be noted in Figures 3 and 4 has frictional support against the movable cutter bar 26 at the center and on a line of contact near the roots of the teeth.

As the cutter bar 26 must move with respect to cutter bar 24 in an amount equal to at least one full tooth, it is necessary that elongated openings as 34 be provided so that cutter bar 26 may encircle the various rivets or machine screws 23. The movable cutter bar 26 is provided preferably near its midpoint with the transverse power strut 36 and in this case the fixed cutter 24 and 65 the base plate 10 must also be relieved as by opening 38 to permit full movement of this lug. Lug 36 is preferably bifurcated to form the two arms 40 and 42 so as to provide, in turn, a yoke at 44 which will operatively engage motor drive arm 46.

70 In Figure 5 I have illustrated one form of vibrator motor of a type that has proved practical in the opera-

tion of this trimming device. Motors however for electric clippers and electric razors have been highly developed and many different mechanisms are available for powering my trimmer. Therefore, the motor shown in Figure 5 is merely for illustrative purposes. In the showing, the vibrator member is provided with a magnetic armature 50, a coupling member 52 and a flexible hinge member 54 which is normally a piece of metal capable of high frequency vibration. Vibrator drive arm 46 is secured to the magnetic armature 50 and moves with it giving an exaggerated movement due to the leverage proportions. Following the usual arrangement the spring pressure of member 54 normally urges the armature 50 away from the electro-magnet coil 56 and to complete the contact between contact members 58 and 60. When contact is made at 62 a flow of current is induced through coil 56 and the armature is attracted to the pole piece 64. In so doing the contact is broken at 62 and the cycle is repeated. A start and stop switch is provided at 64 and an electric conductor housing is provided at 66 for the electric conductors 68 and 69. Following the present showing, spacer member 70 should be of non-conductive material.

Method of operation

This trimming device is used after the showing of Figure 7 in which the cutter head is fitted to the patron's head so that the proper spacing of the hair line from the ear is obtained. In this connection it has been found that the curve as shown in Figure 1 should be formed to the proportions wherein the distance from the lower tip 72 to the high point of the sharp curve at 74 should be approximately 3½ inches. Curves of this proportion will be found satisfactory for the average adult. It is of course conceivable that if exact fittings of various sized persons are desired, the devices could be made in different sizes especially when marginal cuts are to be made in connection with certain "bob" haircuts on women. The term male hair line cuts applies to both men and women. This has not been proved necessary, however, in that with a curve of this order the barber can, by proper swinging of the device, and possibly taking one or two extra cuts, make a wide variety of curves on the hair line with a single cutter head. The angle between the plane of the cutter head as shown in Figure 1 and the axis of housing 20 of the motor unit should then be adjusted to a point of greatest convenience so that the housing will stand well away from the scalp and at a convenient angle to use. Power is then applied through switch 64 to the motor through arm 46, or possibly other arrangements with different styles of driving motors may be used, to cause a rapid reciprocation of cutter bar 26. Now normally the cutter head is not moved to make the trim cut. Consequently the cutter bar 26 only has to be energized for a moment and the trim is completed.

The barber then applies the reverse side of the cutter head to the opposite side of the customer's head. He then adjusts the motor housing 20 in the opposite sense to this previous cut, and in the same manner the trim is made. Both of these cuts can be made very quickly and they will be very similar on both sides of the head. This is very desirable when there is a question of skill on the part of the barber and is a great time saver to him.

It is believed that it will be clearly apparent from the above description and the disclosure in the drawings that the invention comprehends a novel construction of a barber's marginal trimming device.

Having thus disclosed the invention, I claim:

1. A barber's clipper for defining a conventional male hair line above, in front of and behind an ear in a single orientation, comprising: a handle having electric power means, a rigid, elongated base member secured to an end of said handle intermediate the end portions of said base member by hinge means permitting pivoting of said handle laterally of said base member and spring-pressed detent means between said handle and said base member

permitting selective locking of said handle in one position exposing one side edge of said base member and another position exposing the other side edge in a manner permitting application of the side edges to the hair area bordering the ear with the handle extending at an angle to the hair area, an elongated cutter bar positioned on and secured to said base member in axial alignment and means connecting said cutter bar to said power means to oscillate in movement longitudinally of said base member upon energizing of said power means, said cutter bar having cutting teeth on both side edges and said base member having means on corresponding side edges forming stationary, supporting teeth extending outward slightly beyond said cutting teeth forming a rest so that said cutting teeth will not cut the skin of the customer, said base member being curved in a manner so as to approximate the conventional newly-cut hair line above, in front of and behind an ear with the teeth on one side being capable of application to the hair around one ear and the teeth on the other side to the hair around the other ear, said cutter bar being flexible so as to bend as it moves on said base member to follow the curve of said base member.

2. A barber's clipper for defining a conventional male hair line around an ear in a single orientation, comprising: a handle having electric power means, a rigid, elongated base member secured to an end of said handle in a manner so as to be normally stationary in respect to said handle and extending laterally thereof, an elongated cutter bar positioned on and secured to said base member in axial alignment and means connecting said cutter bar to said power means to oscillate in movement longitudinally of said base member upon energizing of said power means, said cutter bar having cutting teeth on both side edges and said base member having means on corresponding side edges forming stationary, supporting teeth, said base member having a shape approximating the conventional newly-cut hair trim line on the side of the head including an upper sharply-curved portion adapted to cut the trim line in front of, above and behind the upper portion of the ear and including a depending relatively straight portion adapted to cut the trim line substantially to the base of the trim line at the neck with the teeth on one side being capable of application to the hair around one ear and the teeth on the other side to the hair around the other ear, said cutter bar being flexible so as to bend as it moves on said base member to follow the curve of said base member.

3. A barber's clipper for defining a conventional male hair line around an ear in a single orientation, comprising: a handle having power means, an elongated base member secured to an end of said handle in a manner so as to be normally stationary in respect to said handle, an elongated cutter bar positioned on and secured to said base in axial alignment and means connecting said cutter bar to said power means to oscillate in movement longitudinally of said base member upon energizing of said power means, said cutter bar having cutting teeth on at least one side edge and said base member having means on a corresponding aligned side edge forming stationary, supporting teeth extending outward slightly beyond said cutting teeth forming a rest so that said cutting teeth will not cut the skin of the customer, said base member having a shape approximating the conventional newly-cut hair trim line on the side of the head including an upper sharply-curved portion adapted to cut the trim line in front of, above and behind the upper portion of the ear and including a depending relatively straight portion adapted to cut the trim line substantially to the base of the trim line at the neck, said cutter bar being flexible so as to bend as it moves on said base member to follow the curve of said base member.

4. A barber's clipper for defining a conventional male hair line above, in front of and behind an ear in a single orientation, comprising: a handle having electric power

means, a rigid, elongated base secured to an end of said handle and extending laterally thereof, an elongated cutter bar positioned on one face of said base member and means connecting said cutter bar to said power means to oscillate in movement longitudinally of said base member upon energizing of said power means, said cutter bar having cutting teeth on both side edges, a stationary bar positioned between said base member and said cutter bar having teeth on its side edges extending outwardly slightly beyond said cutting teeth forming a rest so that said cutting teeth will not cut the skin of the customer, a guard member positioned on the side of said cutter bar opposite said stationary bar, there being securing means securing said guard member, stationary bar and base member together and said cutter bar having slots through which said securing means extend, said slots being longitudinally elongated to permit the oscillation of said cutter bar, said guard member being bowed so as to contact said cutter bar only at the middle and side edges of said guard member to minimize friction therebetween, said base member, stationary bar and guard member being curved in a manner so as to approximate the conventional newly-cut hair line above, in front of and behind an ear with the teeth on one side being capable of application to the hair around one ear and the teeth on the other side to the hair around the other ear, said cutter bar being flexible so as to bend as it moves to follow the curvature of the other members.

5. A barber's clipper for defining a conventional male hair line above, in front of and behind an ear, comprising: 80 an elongated base member having a shape approximating

the conventional newly-cut hair trim line on the side of the head including an upper sharply-curved portion adapted to cut the trim line in front of, above and behind the upper portion of the ear and including a depending relatively straight portion adapted to cut the trim line substantially to the base of the trim line at the neck, an elongated cutter bar positioned on and secured to said base member in axial alignment in a manner permitting longitudinal movement of said cutter bar with respect to said base member while following the curve of said base member, said cutter bar having cutting teeth on at least one side edge and said base member having means forming aligned, cooperating teeth, and power means connected to the cutter bar operable to oscillate said cutter bar longitudinally with respect to said base member when energized.
